[57] CLAIM

The ornamental design for a cologne bottle, as shown and described.

DESCRIPTION

FIG. 1 is a frontal perspective view of a cologne bottle showing my new design;
FIG. 2 is a front elevational view thereof;
FIG. 3 is a top plan view thereof;
FIG. 4 is a side elevational view thereof, the other side elevational view thereof being identical;
FIG. 5 is a bottom plan view thereof; and
FIG. 6 is a cross sectional view thereof taken along the plane of line 6—6 in FIG. 4.
